UNITED STATES PATENT OFFICE.

FRITZ GREINER, OF REINICKENDORF-OST, GERMANY, ASSIGNOR TO OTTO SCHLICK, OF BERLIN, GERMANY.

CARBURETER.

1,153,487.

Specification of Letters Patent. Patented Sept. 14, 1915.

Application filed May 15, 1913. Serial No. 767,805.

To all whom it may concern:

Be it known that I, FRITZ GREINER, of Reinickendorf-Ost, Germany, a subject of the King of Wurttemberg, and whose post office address is 84 Provinzstrasse, Reinickendorf-Ost, near Berlin, Kingdom of Prussia, German Empire, have invented a new and useful Carbureter for Internal-Combustion Engines, of which the following is a specification.

This invention relates to a carbureter for internal combustion engines or the like, and more particularly to a carbureter in which use is made in addition to the main mixing or atomizing device employed for normal working of an auxiliary mixing or atomizing device, which is so constructed as to enable it to be used both for starting the engine and for the slow running of the engine in the case, for instance, in which the engine runs without load.

An important feature of the invention is the particular regulating mechanism for the auxiliary mixing device for the purpose of enabling the latter to perform both the functions referred to in an efficient and as perfect a manner as possible.

A further feature of the invention concerns the regulation of the additional air required in the transition from the slow running to high speeds or in other words from the idle running of the engine to its working under full load and during the regular working thereof.

Another feature of the invention consists in the possibility of exchanging the air and fuel nozzles in the case in which the carbureter is to be adapted for different fuels, for instance, motor-spirit, benzin, heavy benzin or benzol, so as to enable the driver to use one or the other medium without having to detach the carbureter.

A constructional form of the carbureter according to this invention is illustrated by way of example in the accompanying drawings, in which—

Figure 1 is a vertical longitudinal section of the carbureter on the line A—A of Fig. 2. Fig. 2 is a horizontal cross section on the line B—B of Fig. 1, with the float shown removed. Fig. 3 is a vertical longitudinal section on the line C—C of Fig. 1 and showing a view at right angles to the latter with the air nozzle and the fuel nozzle of the main

mixer removed. Fig. 4 is a sectional view 55 of a detail on the line D—D of Fig. 3. Fig. 5 shows a similar section with the controlling member in a different position. Fig. 6 is a horizontal section of the valve casing on the line E—E of Fig. 3. Fig. 7 shows 60 the lid on the valve casing with the adjustable controlling slide for the admission of additional air, and Fig. 8 illustrates the ports in the slide for controlling the admission of the additional air in different positions and on a somewhat enlarged scale.

The carbureter comprises a housing 1 (Figs. 1, 2 and 3), connected at its lower part to the cylindrical fuel container 2, which is cast integral with the housing and 70 with the lateral air inlet chamber 3. The fuel container is provided at its bottom with a socket 4 screwed into which is the connecting socket 5 for the fuel supply conduit. At the top, the fuel container 2 is closed by 75 a lid 6 which is held in closed position by a spring 7 or a like contrivance. The fuel inlet socket 5 forms in a known manner the seat for the stem 8 of an inlet valve which by means of pivoted levers 9 is held in contact with a float 10 adapted to maintain the fuel at a constant level in the usual known manner. Leading from the fuel container to a socket 12 on the air inlet chamber 3 is a passage 11 which is closed by a screw plug 85 13 and into which the fuel nozzle 14 can be screwed from below after removing the screw plug 13. The air inlet chamber 3 is provided laterally with an air inlet socket 15 and with a second air inlet socket 16 of 90 which the one may be closed in a known manner by a cover 17 equipped with a sliding register 18. Leading from the socket 12 laterally to a vertical bore 21 is a further passage 20. The bore 21 may be closed 95 from below by a screw 22, after the removal of which a second small fuel nozzle 23 or nozzle of the auxiliary mixer may be screwed into the bore from below. This auxiliary nozzle is surrounded by a pipe 24 100 which is provided with a circular series of small holes 25. Arranged above the pipe 24 is a bore 26 traversed by a transverse passage 27, the outwardly leading portion of which is closed by a pointed screw 28 forming an inlet valve for the regulation of the terminal leading from the bore 26 to the passage 27.

Adapted to be laterally inserted in the housing 1 is a prismatic central part or bushing 30 which is secured in position to the housing as is shown in Fig. 2 by two screws 31. Capable of being introduced into this bushing 30 is an air nozzle 32 provided with a top flange 33 fitted in a corresponding annular groove in the bushing 30. The housing 1, as shown in Fig. 3, is provided with a lateral tubular projection or socket 35 having a cylindrical bore which is adapted to be closed by a screw plug 36. Inserted in the cylindrical bore is a cylindrical nipple 37 which has an eccentric bore 38 and on one of its faces a groove 39 enabling after removal of the screw plug 36 a screwdriver or like tool to be introduced into the groove for the purpose of rotating the nipple 37 and thereby adjusting the position of the eccentric passage 38, as indicated in Figs. 4 and 5. Inserted in the upper part of the tubular socket 35 is a short pipe 40 having air inlet openings 41 and being surrounded by a rotary sleeve 45 which is provided with similar openings 42.

The upper portion of the housing 1 is constructed to form a valve casing 50 rotatably journaled in which on a shaft 52 is the distributing valve or throttle 51. As shown in Fig. 3 this valve 51 is provided with a small opening 53 which in the position shown in Fig. 3 registers with the lateral passage 27. In the rotation of the valve 51 in the direction of the arrow shown in Fig. 3, the passage 27 is closed and at the same time the path is freed for the mixture to pass through the nozzle 32 to the mixture feed pipe 54. This pipe is provided with a flange 55 for the usual connection to the valve casing of the engine. The rotation of the distributing valve 51 is effected by means of a lever 56 which is secured at the outside of the lid 60 to the shaft 52 of the throttle 51. The lid 61 on the other side of this casing is provided with a stop pin 58, whereby the rotation of the valve to the position shown in Fig. 3 is suitably confined. Arranged in the wall of the valve 51 and facing the lid 61 are openings 57, and rotatably mounted on the shaft 52 on the outside of the lid 61 is a slide 62 provided with an annular flange 63 which is adapted to overlap the edge of the valve casing 50. Provided in this edge are four openings 64, 65, 66 and 67, as shown in Fig. 6, of different diameters, and arranged in the flange 63 are four openings 68, of equal and the same diameter as the opening 67. In the face portion of the slide 62 is a curved slot 69 projecting through which is a set screw 70 by means of which the slide can be secured in its adjusted position. Wire netting 71 is arranged to cover the openings 68 in the slide 62 externally, so as to prevent dust or other foreign bodies from entering the open-

ings, and a similar but cylindrical wire netting 72 is arranged within the air inlet socket 40, as shown in Fig. 3.

The operation of this carbureter is as follows:—Before starting the engine the fuel admitted at 5 to the receptacle 2 under the influence of the float 10 and the needle valve 8 assumes the level indicated in Fig. 1 and rises to a corresponding level in the main fuel nozzle 14 close to its terminal. In the auxiliary mixer the fuel rises in the pipe as shown in Fig. 3 to a level which is above the terminal of the auxiliary fuel nozzle 23, because the upper edge of this nozzle 23 and the small holes 25 in the pipe 24 are situated slightly lower than the upper edge of the terminal of the fuel nozzle 14 in the main carbureter portion. By adjusting the rotary nipple 37 with its eccentric bore 38, as indicated in Figs. 4 and 5, the cross section of the air passage above the fuel level may be suitably varied. In the position of the nipple 37, as shown in Figs. 3 and 4, in which the eccentric bore 38 is in its highest position the fuel lies relatively low in the eccentric opening and thus frees the substantially large opening for the passage of the air. In the lowest position of the eccentric passage 38, however, as shown in Fig. 5, the relation is reversed inasmuch as the fuel almost completely closes the air passage opening leaving only a very narrow gap for the passage of the air. In the intermediate positions the relation is accordingly different. It is thus possible to regulate both the quantity of fuel located in front and above the terminal of the fuel nozzle 23 and also the free cross section of the air passage above the level of the fuel. The valve 51 is at the outset in the position shown in Fig. 3, in which the opening 53 communicates with the passage 27, while the passage from the air nozzle 32 to the feed socket 54 is entirely closed by the throttle. In this position of the valve the latter also closes the whole of the openings 64 to 67 arranged for the admission of the auxiliary air. In starting the engine air is sucked on by the cylinder through the ports 41, the eccentric passage 38, the small holes 25, the passages 26 and 27 through the opening 53 and carries with it into the mixture socket 54 and the valve casing the whole of the fuel located above the terminal of the nozzle 23 in the auxiliary mixer. For the first ignition, therefore, a mixture very rich in fuel is sucked on and atomized by the nozzle 23 and the walls of the passages of this mixture are finely wetted with fuel, thus enabling the motor to start easily upon ignition. As soon as, after the engine is started by the explosions of this mixture, the fuel previously located above the nozzle is sucked on, during each stroke only little fuel and a relatively large quantity of air 130

are utilized in forming a poor mixture in the auxiliary mixer such as suffices for the slow running or idle working of the loadless engine. By means of the lever 56 the valve 51 is then rotated in the opening sense in the direction of the arrow shown in Fig. 3, whereby the passage 27 is closed and the auxiliary mixer is cut off, and simultaneously therewith the main mixer is rendered operative, in which procedure, according to the extent of rotation of the valve, the openings 64, 65, 66 and 67 for the admission of auxiliary air are consecutively freed so that when the distributing valve 51 is only slightly opened, first of all the smallest opening 64 is freed, whereas the whole of the openings 64 to 67 are uncovered when the valve 51 is opened to its full extent. In these positions of the valve 20 the required explosive mixture is supplied in the known manner from the main mixer through the fuel nozzle 14 and the air nozzle 32. The quantity of the air for the mixture may be adjusted in the main mixer 25 by the slide 18 and for the auxiliary mixer by means of the slide 45 and in the same manner the quantity of the auxiliary air can be adjusted with the aid of the slide 62. Owing to the mutual location and sizes of 30 the openings 64, 65, 66 and 67 on the one hand, and the openings 68 on the other hand, the auxiliary air can never be entirely cut off by the adjustment of the slide 62, for even in the closing position, as 35 shown in the bottom portion of Fig. 8, a small cross sectional passage is always held open, thus insuring that auxiliary air can always enter the mixture socket 54 through these openings and the openings 57 as soon 40 as the valve 51 has freed the second sized opening 65 and in all the further opening positions of the valve. Upon the quantity of the additional air being adjusted by means of the slide 62 for a particular engine, the 45 binding screw 70 is tightened, whereby the slide is secured in its adjusted position.

If with the same engine it is desired to use a different fuel, for example, benzol, or kerosene, instead of benzin, the screws 31 50 are loosened and the bushing 30 is laterally withdrawn after previously removing the screw plug 13 and unscrewing the fuel nozzle 14 by means of the wrench-shaped head of the plug 13. From the bushing 30 55 thus withdrawn the air nozzle 32 employed for the working with benzin is withdrawn in upward direction, and a somewhat wider nozzle suitable for benzol is inserted thereon from above, the edge 33 therein serving as 60 a safeguard for its correct insertion. The bushing 30 with the new nozzle is then reinserted laterally and secured in position by the screws 31. In the place of the fuel nozzle 14 a somewhat enlarged fuel nozzle is 65 then screwed in from below for the use of

the heavier oil and the closing plug 13 is refitted. By this simple manipulation the carbureter is ready for the new fuel. If it is required to introduce warm air instead of cold air, the socket 16 may be connected 70 to a hot air conduit, but experience has shown that with the carbureter arranged and constructed as above described admission of hot air is necessary only in special cases, even if benzol, kerosene, paraffin or 75 other fuel is used.

What I do claim as my invention, and desire to secure by Letters Patent of the United States, is:—

1. In a carbureter the combination with 80 a main mixing device of an auxiliary mixing device and controlling means for the said auxiliary mixing device comprising an adjustable rotary member provided with an eccentric passage and means for adjusting said member so as to vary the level of fuel in the said eccentric passage through which the air is drawn to form the mixture, substantially as set forth.

2. In a carbureter the combination with 90 a main fuel nozzle and an air nozzle of an auxiliary mixing device comprising an auxiliary fuel nozzle located at a lower level with regard to the said main fuel nozzle, an auxiliary mixture conduit, ports, in the said 95 conduit, and located above and around the terminal of the said auxiliary fuel nozzle, an adjustable cylindrical member with an eccentric passage communicating with the ports in the said mixture conduit and an air register adapted to control the flow of air 100 through the said eccentric passage across the fuel located above the terminal of the auxiliary fuel nozzle, substantially as set forth.

3. In a carbureter the combination with a 105 main mixing device of an auxiliary mixing device, a distributing valve arranged in the main mixture conduit, a casing for the said valve connected with both the main and the auxiliary mixture conduits, a series of air ports of different diameters in the casing, a slide adjustably mounted on the said casing, and provided with a corresponding number of air inlets but of equal diameter 110 adapted to register with the said air ports so that a certain amount of auxiliary air 115 is always admitted to the said casing, substantially as set forth.

4. In a carbureter the combination with a 120 main fuel nozzle of a main air inlet nozzle and a removable bushing slidable transversely into and out of position in the main air duct and means for securing the said inlet nozzle in the said bushing and means for securing the said bushing in the said air duct, substantially as set forth.

5. In a carbureter the combination with a 125 main fuel nozzle of a main air inlet nozzle and a removable bushing slidable transversely into and out of position in the main 130

- air duct, an annular flange on the said air inlet nozzle and an annular groove in the said bushing adapted to receive and to seat the air inlet nozzle, substantially as set forth.
6. In a carbureter the combination of a detachable main fuel nozzle, a detachable air inlet nozzle, a detachable bushing slidable transversely into and out of position and adapted to receive and to seat the air inlet nozzle, a detachable auxiliary fuel inlet nozzle and a distributing valve arranged to con-

trol simultaneously the main and the auxiliary mixture conduit with means for controlling the admission of auxiliary air, all substantially as described.

In testimony whereof I have hereunto set my hand in presence of two subscribing witnesses.

FRITZ GREINER.
